COMBINATION BUNK BED AND SOFA

Samuel D. Neyman, Fayetteville, Tenn.
(5015 Parkwood Drive NW, Huntsville, Ala. 35810)

Filed Apr. 26, 1974, Ser. No. 464,912

Term of patent 14 years

Int. Cl. D6—06

U.S. Cl. D6—4

Fig 1

Fig 2

Fig 3

Fig 4

FIG. 1 is a perspective view from the front showing my new design;

FIG. 2 is an end elevation, the opposite end being the reverse of this view;

FIG. 3 is a perspective view from the rear; and

FIG. 4 is a top plan view.

I claim:

The ornamental design for a combination bunk bed and sofa, substantially as shown.
